DESIGN FOR A DUAL CONTROL FOR PHONOGRAPHS

Louis Z. La Forest, Parsippany-Troy Hills Township, Morris County, N. J., assignor to Thomas A. Edison, Incorporated, West Orange, N. J., a corporation of New Jersey

Application June 27, 1942, Serial No. 107,360

Term of patent 14 years

To all whom it may concern:

Be it known that I, Louis Z. La Forest, a citizen of the United States, residing at Parsippany-Troy Hills Township, in the county of Morris and State of New Jersey, have invented a new, original, and ornamental Design for a Dual Control for Sound Reproducer or Similar Article, of which the following is a specification, reference being had to the accompanying drawing, forming a part thereof.

In the drawing:

Figure 1 is a front perspective view of a dual control for a sound reproducer showing my new design;

Figure 2 and 3 are respectively opposite end elevational views thereof; and

Figure 4 is a rear elevational view thereof.

I claim:

The ornamental design for a dual control for a sound reproducer or similar article, substantially as shown.

LOUIS Z. LA FOREST.

CERTIFICATE OF CORRECTION.

Design No. 135,266.

LOUIS Z. LA FOREST.

It is hereby certified that error appears in the above numbered patent
Grant correction as follows: In the grant, line 7, and in the heading
the specification and drawings, title of invention, for "A DUAL CONTROL
FOR PHONOGRAFS" read --A DUAL CONTROL FOR SOUND REPRODUCER OR SIMILAR
ARTICLE--; and that the said Letters Patent should be read with this cor-
rection therein that the same may conform to the record of the case in the
Patent Office.

Signed and sealed this 11th day of May, A. D. 1943.
